ILLUMINABLE SHELF

Larry Garbett, 11231 SW. 70th Ave.,
Miami, Fla. 33156

Filed Jan. 10, 1966, Ser. No. 554

Term of patent 14 years

(Cl. D33—3)

FIG. 1

FIG. 2

FIG. 3

I claim:

The ornamental design for an illuminable shelf, substantially as shown and described.
